UNITED STATES PATENT OFFICE

ETHAN I. DODDS, OF PULLMAN, ILLINOIS, ASSIGNOR TO THE PULLMAN COMPANY, OF CHICAGO, ILLINOIS, A CORPORATION OF ILLINOIS.

METALLIC CAR-BOLSTER.

No. 825,030.

Specification of Letters Patent.

Patented July 3, 1906.

Application filed August 23, 1905. Serial No. 275,381.

To all whom it may concern:

Be it known that I, ETHAN I. DODDS, a citizen of the United States, residing at Pullman, in the county of Cook and State of Illinois, have invented certain new and useful Improvements in Metallic Car - Bolsters, of which the following is a specification.

My invention concerns car-bolsters, and particularly relates to such devices employing a bottom tension or compression plate which tapers toward both ends. In order to use such a plate, I rivet a comparatively short angle-bar to the central part of each side plate of the bolster near its lower edge and with one flange extended outwardly. Along the remaining portions of the lower edges of the side plates there are provided in-turned flanges, the tapered bottom plate being fastened to the outstanding flanges of the angle-bars and to the in-turned flanges of the side plates. At the upper edges of the side plates are riveted other angle-bars with outwardly-extended flanges, to which is secured the top plate of the bolster.

25 In the accompanying drawings, which form a part of this specification, and wherein like reference characters refer to like parts, I have illustrated two embodiments of my invention.

30 Figure 1 is a perspective view of a truck-bolster embodying my invention, the same having integral in-turned flanges along portions of the lower edges of its side plates. Fig. 2 is a longitudinal section of both the 35 body and truck bolsters, each with integral in-turned flanges. Fig. 3 is an enlarged end view of both bolsters. Fig. 4 is a central transverse section of both bolsters, the combined spacer and king-pin bearing members 40 being partly broken away. Fig. 5 is a perspective view of a truck-bolster having in-turned flanges along the lower edges of its side plates, the flanges comprising angle-bars riveted to said side plates. Fig. 6 is a longitudinal section of both the body and truck 45 bolster involving the features shown in Fig. 5. Fig. 7 is an enlarged end view of both bolsters shown in Fig. 6. Fig. 8 is a central transverse section of both bolsters.

50 Referring first to Figs. 1, 2, 3, and 4, it will be seen that the bolster has two bellied side plates 10 10, to which are attached at the central portion of their lower edges the comparatively short angle-bars 11 11, having

outwardly - extended flanges, as is clearly 55 shown in Figs. 1 and 4. On the intermediate inclined and horizontal end portions of the lower edges of the side plates are integral in-turned flanges 12 12, the bottom plate 13, which is broadest at its central part and 60 tapers toward its ends, being secured by means of rivets to these outwardly and inwardly extended flanges. Along the upper edges of the side plates are provided angle-bars 14, which are riveted to the side plates 55 with their flanges extended outwardly, the top plate 15 being riveted to these flanges, as shown in Figs. 1, 3, and 4. The top plate and the upper angle-bars extend substantially the whole length of the body-bolster, 70 while the corresponding parts for the truck-bolster extend only a portion of the length thereof, as will be clearly evident from an inspection of Figs. 1 and 2. To space apart and at the same time secure together the side 75 plates, I provide at the ends of the body-bolster the dish-shaped members 16, which are riveted to the sides and bottom, the rivets also passing through the upper angle-bars and the lower in-turned flanges. For the 80 truck-bolster I employ two dish-shaped members 17, as shown in Fig. 1, the same being riveted to the sides and guide-plates 18 and to the bottom plate and in-turned flanges. 85

The bolsters illustrated in Figs. 5 to 8, inclusive, are similar to those described above; but instead of having integral inwardly-extended flanges along the lower edges of the side plates they have angle-bars 19 with in-turned flanges, which are riveted to the side 90 plates. The dish-shaped members 20 and 21 for the body and truck bolsters, respectively, differ somewhat in shape from those shown in Figs. 1, 2, and 3 to provide for these extra angles. They are riveted to the sides, upper 95 angle-bars, bottom plate, and lower in-turned angle-bars.

By using upper and lower angle-bars separate from the side plates and riveting them thereto I am enabled to use bars of different sizes and strengths in accordance with the kind of cars the bolsters are to be embodied in. By fastening the angle-bars so that they extend beyond the edges of the side plates, with their flanges above and below the upper and lower edges thereof, respectively, I am enabled to increase to some extent the depth of the side plates, thus varying the 100 105

strength of the bolster and proportioning it to properly withstand the strains to which it may be subjected.

It will be obvious to those skilled in the art that various changes in the details of these structures may be made without departing from the substance of the invention as defined in the appended claims. I do not, therefore, limit myself to these details except to the extent indicated in the specific claims following.

This patent is intended to embrace only so much of the disclosure made herein as is covered by the claims.

15 I claim—

1. A car-bolster, comprising two side plates, an angle-bar riveted to each of said plates along the central portion of its lower edge, each of said plates having integral flanges 20 along the end portions of its lower edge, and a bottom plate riveted to said flanges and angle-bars, substantially as described.

2. A car-bolster, comprising two side plates, an angle-bar riveted to each of said plates 25 along the central portion of its lower edge with one flange extended outwardly, each of said side plates having integral inturned flanges along the end portions of its lower edge, and a bottom plate riveted to the outwardly-extended flanges of said angle-bars and to the integral flanges of said side plates, substantially as described.

3. A car-bolster, comprising two side plates, an angle-bar riveted to each of said plates 35 along the central portion of its lower edge with one flange extended outwardly, each of said side plates having integral inturned flanges along the end portions of its lower edge, and a bottom plate tapering toward its 40 ends riveted to the outwardly-extended flanges of said angle-bars and to the integral flanges of said side plates, substantially as described.

4. A car-bolster, comprising two bellied side plates, an angle-bar riveted to each of said plates along the central portion of its lower edge with one flange extended outwardly, each of said side plates having integral inturned flanges along the end portions 50 of its lower edge, and a bottom plate riveted to the outwardly-extended flanges of said angle-bars and to the integral flanges of said side plates, substantially as described.

5. A car-bolster, comprising side plates

each with an outwardly-extended flange 55 along the central portion of its lower edge, and inwardly-extended flanges along the end portions of its lower edge, an angle-bar riveted to each side plate adjacent to its upper edge, and a bottom plate riveted to said 60 lower flanges, substantially as described.

6. A car-bolster, comprising two side plates, an angle-bar riveted to each of said plates adjacent to its upper edge, an angle-bar riveted to each of said plates along the central portion of its lower edge, each of said side plates having integral flanges along the end portions of its lower edge, and a bottom plate riveted to said flanges and lower angle-bars, substantially as described. 70

7. A car-bolster, comprising two side plates, an angle-bar riveted to each of said plates adjacent to its upper edge, an angle-bar riveted to each of said plates along the central portion of its lower edge with one flange extended outwardly, each of said plates having integral inturned flanges along the end portions at its lower edge, and a bottom plate riveted to the outwardly-extended flanges of said lower angle-bars and to the flanges of said 80 side plates, substantially as described. 75

8. A car-bolster, comprising side plates, an angle-bar riveted to the outer side of each of said plates adjacent to its upper edge and with a flange extended outwardly, each of said side plates having an outwardly-extended flange along the central portion of its lower edge and inwardly-extended flanges along the end portions of its lower edge, and a bottom plate riveted to said lower flanges, substantially as described. 85

9. A car-bolster, comprising two side plates, an angle-bar riveted to each of said plates adjacent to its upper edge and with a flange extended outwardly, an angle-bar riveted to 95 each of said plates along the central portion of its lower edge, each of said side plates having an integral flange along the end portions of its lower edge, a top plate riveted to the outwardly-extended flanges of the upper angle-bars, and a bottom plate riveted to the integral flanges of the side plates and to the lower angle-bars, substantially as described. 100
